BRACELET

Charles Lee MacIntosh, Attleboro, Mass., assignor
to S. O. Bigney & Company, a corporation of
Massachusetts

Application November 26, 1935, Serial No. 51,608

2 Claims. (Cl. 63—11)

This invention relates to a bracelet, and has for one of its objects the provision of a bracelet which may be expanded and contracted without the use of separate halves with a hinge connection between for one-half of the bracelet to swing with reference to the other half of the bracelet.

Another object of the invention is the provision of a bracelet which is stiff when in closed position and yet one which may be easily moved from closed to open position or vice versa without the use of a joint and catch for clasping the parts in closed position.

Another object of the invention is the utilization of resiliency in the band for holding the parts in closed position and permitting them to be easily moved to open position for removal of the device from the wrist of the wearer.

Another object of the invention is the provision of a bracelet, the mechanical parts of which may be entirely concealed when in closed position and yet so arranged as to be out of contact with the wrist so as to not to abrade or injure the wrist of the wearer.

Another object of the invention is a simple and yet effective means of mounting and retaining the links which connect the parts in their desired relation thereby effecting an assembly of the parts which may be quickly made.

With these and other objects in view, the invention consists of certain novel features of construction, as will be more fully described, and particularly pointed out in the appended claims.

In the accompanying drawing:

Fig. 1 is a perspective view of the bracelet in closed or contracted position;

Fig. 2 is a perspective view showing the buckle portion raised in swinging the links from closed to open position;

Fig. 3 is a perspective view of the band portion of the bracelet and the links with the buckle detached;

Fig. 4 is a plan view of the underside of the buckle;

Fig. 5 is a sectional view on line 5—5 of Fig. 4; Fig. 6 is a sectional view on line 6—6 of Fig. 4;

Fig. 7 is a central sectional view of the bracelet in closed or contracted position;

Fig. 8 is a sectional view on line 8—8 of Fig. 7;

Figure 9 is a sectional view on line 9—9 of Fig. 7.

The usual bracelet which is stiff upon the wrist is either formed in halves with a hinge connection at one of the ends of the halves and a catch at the other end, or if it is resilient there is usually some latch and catch to secure the ends

separably together so that the catch may be detached and the ends of the bracelet flexed open permitting it to be taken from the wrist; and in order to avoid both hinges and latches and catches, I have provided a construction utilizing the resiliency of the encircling band but providing a buckle connected by links to the ends of the band which may be easily moved from open or expanded position to contracted position or vice versa without the disconnection and complete separation of the parts, the connecting links supplying the additional length necessary for enlarging the encircling size to permit the bracelet to be withdrawn over the hand of the wearer; and the following is a more detailed description of the present embodiment of this invention, illustrating the preferred means by which these advantageous results may be accomplished:

With reference to the drawing, 10 designates a band bent generally circularly, as shown in Fig. 3, so that when at rest it will assume the shape substantially shown in Fig. 3, with its ends 11 and 12 spaced as there shown, the band being of some sort of material sufficiently resilient to permit these ends to be spread when enlarging the general encircling size of the device or to be contracted to decrease the general encircling size of the band.

The ends of this band are rolled inwardly as at 13 to provide eyes 14 which receive generally U-shaped connecting links 15, each comprising legs 16 and a connecting portion 17 joining these legs and pivotally mounted in the eyes 14 on the ends of the band. The end of each of these legs is turned outwardly as at 18 to be pivotally mounted in a buckle such as shown in Fig. 4. This buckle is designated generally 19 having side flanges 20 with inwardly extending lips 21 which carry upwardly turned ears 22 pierced to receive the fingers 18.

The overall length of the buckle 19 is such that it will cover or span the space between the ends of the band when the same is at normal or rest position. The links 15 are connected to the buckle by compressing the legs 16 toward each other and permitting the outwardly extended fingers 18 to snap into the opening in the ears 22 which are opposite each other on the lips 21. The connecting arrangement being such as shown in Fig. 2, or in Fig. 5.

To move the bracelet to its contracted position the ends 11 and 12 are swung inwardly being bent downwardly somewhat from the at rest position as shown in Fig. 3, and then upwardly to lie snug-

ly between the top surface of the buckle 19, in which position the rolled portion 13 will lie inwardly from the lips 21 of the flanges 20 and be prevented from contacting with the wrist of the wearer. Further, by being located in the position as shown in Fig. 7 the resiliency of the band which is now under some constriction will be held firmly in closed position, as shown in Fig. 7. To move the bracelet to expanded position it is merely necessary to move downwardly and outwardly one of the end portions of the band, such as 12, and then to follow it by similarly moving the opposite end portion of the band such as 11. The enlargement afforded by reason of the movement of each of the links through substantially 180° will be four times the length of the link which are of equal length, thus affording easy removal of the bracelet from the wrist of the wearer.

The foregoing description is directed solely towards the construction illustrated, but I desire it to be understood that I reserve the privilege of

resorting to all the mechanical changes to which the device is susceptible, the invention being defined and limited only by the terms of the appended claims.

I claim:

1. A bracelet comprising a buckle having depending side flanges, inwardly extending lips carried thereby, and upturned ears carried by said lips and apertured to receive the ends of links, a resilient band for substantially encircling the 10 wrist with its ends spaced, and links pivoted to the ends of said band and to said upturned ears.
2. A bracelet comprising a resilient band for substantially encircling the wrist, a buckle having side depending flanges, inwardly extending lips 15 carried by said flanges and upwardly turned ears carried by said lips and apertured to receive the ends of links, said band having its ends rolled to provide pivots, and links pivoted in said rolled ends and in said upturned ears.

CHARLES LEE MACINTOSH.
